UNITED STATES PATENT OFFICE

EDWARD O. TINSLEY, OF NEW YORK, N. Y., ASSIGNOR TO ROBERT GAIR COMPANY, OF NEW YORK, N. Y., A CORPORATION OF NEW YORK

COLLAPSIBLE DISPLAY CONTAINER

Application filed April 21, 1928. Serial No. 271,850.

This invention relates to display containers and methods of filling them and removing articles therefrom and more particularly to the kind having lids serving to close the container as for shipping and also as a display space for advertising, ornament and the like, though it is noted that the invention is not limited to display containers nor to methods.

10 One object of the invention is to provide a method and container of this kind permitting the container to be conveniently filled or packed with articles inserted at one end or part of the container by means of filling machines now well known upon the market, and after filling and closing to be suitably opened at another part for removal or display.

Another object of the invention is to provide a container of this kind having a folding display lid suitably formed to hold itself in display position.

Other objects of the invention are to provide a container of the above kind which 25 may be shipped or packed as a one-piece blank, or may be easily assembled and folded flat for packing or shipping and may be easily assembled or unfolded for use.

Another object is to provide a container 30 of this kind having one face adapted for display printing and comprising all of the parts which are exteriorly exposed when the container is closed, and comprising, when the lid is open, all of the exterior part of 35 the box and the forwardly exposed part of the display portion and lid.

Other objects of the invention are to improve generally the simplicity and efficiency of such containers and to provide a device 40 of this kind which is durable and reliable in use, and economical to manufacture.

Still other objects of the invention will appear as the description proceeds; and while herein details of the invention are described and claimed, and invention is not limited to these, since many and various changes may be made without departing from the scope of the invention as claimed in the broader claims.

50 The inventive features for the accomplish-

ment of these and other objects are shown herein in connection with two improved containers each of which, briefly stated, comprises a blank cut and folded to form a box portion having front rear and end walls, 55 and a lid joining the rear wall and provided with a wide front flap disposable against the front wall and having a tab attachable to the bottom.

One form has tucking flaps joining end 60 edges of the lid, which flaps are adapted to be tucked inside the container or to form extensions of the lid. In this form the lid and extensions are provided with fold lines along the main axis of the lid at the end 65 edges of the lid, the lid being partially cut through from said points to points nearer the inner edge of the lid to form a display portion and foldable upon itself as to permit the display portion to be upwardly disposed and the ends of the extensions to the rest over the end walls of the container. 70

In either form the container is easily disposed in open condition at either end for filling, and its lid is easily openable for 75 display or removal of articles therein.

In the accompanying drawing showing, by way of example two of many possible embodiments of the invention,

Fig. 1 is a perspective view of one form 80 of the container in closed condition;

Fig. 2 is a perspective view of this container in open position ready for filling;

Fig. 3 is a fragmental perspective view of one end of the container in partly closed 85 condition;

Fig. 4 is a fragmental perspective view of said end in nearly closed condition;

Fig. 5 is a fragmental perspective view of an end of the container completely closed; 90

Fig. 6 is a perspective view of the container, open and in display condition;

Fig. 7 is a fragmental vertical sectional view, partly in elevation, showing the lid, front flap and attaching tab, the section being taken through the tab; 95

Fig. 8 is a fragmental end elevation showing the container folded flat;

Fig. 9 is a face view showing the blank from which this container is formed; 100

Figs. 10 and 11 are perspective views showing the other form of container with the ends nearly closed and entirely open, respectively;

5 Fig. 12 is a face view of the blank for making the container of Figs. 10 and 11; and

Fig. 13 is a transverse sectional view taken on the lines 13—13 of Fig. 10, looking in the direction of the arrow of said line.

10 My improved container 10 of Figs. 1 to 9 is made of a one-piece blank 11 (Fig. 9) cut and folded to form a container or box portion comprising a wide bottom 12 (Figs. 4, 7 and 9), end walls 13 foldably joining the end edges 15 of the bottom and front and rear walls 14 and 15 (Figs. 3 and 6) joining the front and rear edges respectively of the bottom, and each provided at each end edge with an inwardly folded corner flap 16 disposed along 20 and secured by adhesive 17 (Fig. 4) to the adjacent portion of the inner face of the adjacent end walls 13.

While the rear and front walls are shown as having the same height, and the end walls 25 are rectangular rather than tapering, the invention is not thus limited.

20 A lid 20 hingedly joining the upper edge of the rear wall and adapted to extend across from wall to wall is provided at the front edge with a front flap 21 foldably joining the lid along the entire front edge of the lid and substantially covering the front wall and provided at the mid part of its lower edge with a closing tab 22 foldable, weakened and 35 severable along the line 23 of the lower edge of the flap and secured by adhesive to the under face of the bottom 12.

Tucking flaps 25 foldably joining the respective end edges of the lid are adapted, 40 when the lid is closed, to be tucked in the container (Figs. 1, 3 and 4) and lie flat against said corner flaps 16 (Fig. 4).

Said tucking flaps are disposable outwardly in the plane of the lid 20 (Fig. 2) to form 45 extensions of the lid, said lid and extensions being provided with fold or score lines 26 substantially coincident with the longitudinal main axis of the lid and extending from the free edge of the extensions to points 27 50 some distance from the end edge of the lid.

The lid is provided with a cut 30 preferably symmetrical to the minor transverse axis of the lid, and extending as at 31 to near the inner edge of the lid to form a display portion 32 in part bounded by the cut.

55 The cut 30 is almost but not entirely cut through the lid and is sufficiently uncut to hold the lid intact before the cut is broken through, thereby to hold articles in the container for shipping and storage.

However said cut 30 is adapted when said tab 22 is broken at the severable line 23, to be broken entirely through to permit the display portion 32 to be projected (Fig. 6) from 65 the cut, and to permit the lid 20 and the ex-

tended extensions 25 to be folded along the lines 26 until the parts of the inner face of the lid on each side of the fold lines engage each other, thus permitting the front flap 21 of the lid to be tucked against the back wall 15 (Fig. 6) behind material or articles in the container, to hold the lid folded and to hold the display portion 32 projected upwardly, with its outer face faced forward, for the display of advertising or other 75 printed matter thereon.

In this position the end portions of each extension 25 are folded flat against each other and project over, and may partly rest on, the upper edge of the end walls.

80 The blank 11 (Fig. 9) is provided with suitable score or fold lines 23, 26 and 37 whereby the various parts hereinbefore mentioned are foldable. This permits the container to be first folded to the form shown in Fig. 2 after which the tab 22 may be secured by adhesive to the container bottom. In this position the end flaps, end walls and tucking flaps are extended.

85 The container, when the corner flaps 16 and container end walls 13 and the tucking flaps 25 are open and extended as in Fig. 2, is adapted to receive, and be packed with a pack 35 of articles which it is to receive, the container being particularly suitable for accomplishing such packing by means of the ordinary packing and filling machines now 90 on the market. After the container is thus filled with the articles, the end walls 13 are secured to the corner flaps 16 by adhesive 17. When the articles are to be displayed or removed, the tab 22 is severed and the lid 95 opened.

100 One face of said blank 11 is particularly adapted for display printing since it comprises all of the parts which are exteriorly exposed when the container is closed as in Fig. 1 and comprising; when the lid is open, all of the exterior part of the box itself, the forwardly exposed part of the display portion 32 and lid and all of the exposed parts of the extended tucking flaps 25.

105 When the end walls 13 and flaps 16 and 25 are open and extended as in Fig. 2, and said closing tab 22 secured or unsecured, the container is adapted to be folded flat upon itself at the front or rear edge of the bottom 12 and the opposite edge of the lid 20 to form a flat article (Fig. 8) for shipping or storing.

110 The container 40 shown in Figs. 10 to 13 comprises a blank 41 (Fig. 12) cut and folded to form a bottom 42, end closure walls 43, and front and rear walls 44, 45 foldably joining the end, front and rear edges of the bottom, the walls 44, 45 being each provided 115 with corner flaps 46 disposable across the ends of the container as in Figs. 11 and 13. The end closure walls 43 are engageable against the outer face of the corner flaps 46 and are each provided with a tucking flap 47 fold- 120

ably joining the free edge of the closure wall and disposable over the top edge of the corner flaps 46.

5 A lid 50 joining the upper edge of the rear wall and engageable with the top face of the tucking flaps when tucked is provided with a front flap 51 foldably joining the free edge of the lid and disposable against the front face of the front wall 44 and provided at its free edge with a severable tab 52 connected to the front flap by the severable fold line 53 and adapted to be secured by adhesive to the bottom face of the bottom.

10 The blank 41 is provided with score or fold lines 53 and 57 by which the various parts 15 of the container are foldably connected.

15 The filling, display, packing and other manipulation is substantially the same for the container of Figs. 10 to 13 as for the other container, except that the tucking flaps are tucked against the lid and the end walls need not be otherwise secured, and the lid is not foldable, though this form of the invention is not limited to the unfolded lid.

20 While in this specification and claims I speak of the bottom, top, ends front and rear of the container and mention that parts are foldably joined, it is understood that I use these words for designation and they are to be construed broadly enough to cover the box in other position, or relative dimensions and when parts are connected by other than score lines, and in general the terms are to be given the broadest interpretation possible.

25 I claim as my invention:

1. A container comprising a box portion; a lid for the box portion provided with a front flap having a tab attachable to the bottom of the box portion, said tab being scored at the inner edge thereof, for readily detaching said front flap therefrom and tucking flaps joining the ends of the lid and adapted to be tucked inside the container or to form extensions of the lid; said lid and extensions being collapsible along the main axis of the lid transversely of said tucking flaps.

30 2. A container comprising a bottom; front, rear and end walls; a lid joining the upper edge of the rear wall and provided with a front flap disposable against the front wall and provided with a tab secured to the under face of the bottom, said tab being scored at the inner edge thereof, to be readily detachable from the front flap; tucking flaps joining end edges of the lid and adapted to be tucked inside the container or to form extensions of the lid; said lid and extensions having alined longitudinal fold lines at the ends of the lid at said extensions reaching to points some 35 distance from the edges of said lid; the lid being partially cut through from said points to near the inner edge of the lid to form a display portion and adapted with said extensions to be collapsed upon itself along the 40 fold lines.

3. A container comprising a box portion; and a lid for the box portion provided with a front flap having thereon a tab attachable to the bottom of the box portion, said tab being scored at the inner edge thereof and 45 tucking flaps foldably joining the ends of the lid and adapted to be tucked inside the container or to form extensions of the lid; said lid and extensions being collapsible along the main axis of the lid transversely to said extensions, thereby permitting the end edges 50 of the extensions to rest on the top edge of the end walls.

4. A container comprising a one-piece blank cut and folded to form a container or box portion comprising a wide bottom; end walls foldably joining the end edges of the bottom; front and rear walls foldably joining the front and rear edges respectively of the bottom, and each provided at each end edge with an inwardly folded corner flap disposed along and secured to the adjacent portion of the inner face of the end walls; a lid hingedly joining the upper edge of the rear wall tucking flaps joining end edges of the lid and adapted to be tucked inside the container; said tucking flaps being adapted to form extensions of the lid; said lid and extensions having fold lines substantially along the main axis of the lid transversely 55 to said extensions, whereby said lid and said extensions may be collapsed and said lid being provided with severable means adapted to be secured to said bottom.

5. A container comprising a box portion 100 front rear and end walls; a lid joining the rear wall; and tucking flaps joining end edges of the lid and adapted to be tucked inside the box or to form extensions of the lid; said lid and extensions being foldable along the main axis of the lid at the edges of the lid and extensions; the lid being partially cut through from points to points nearer the inner edge of the lid and foldable upon itself to permit the collapsing of said lid with said extensions and the ends of the extensions to be projected over the end walls, said lid being provided with severable means 105 secured to said bottom.

6. A container comprising a box portion; a lid for the box portion having a fold line along its main axis whereby said lid may be collapsed and provided with a front flap foldably joining the lid along the entire front edge of the lid and substantially covering the front wall and provided at the mid part of its lower edge with a closing tab foldable, weakened and severable along the line of the lower edge of the flap and secured to the under face of the bottom.

7. A container comprising a box portion having front, rear and end walls; a lid joining the rear wall and provided with a front flap disposable against the front wall and having thereon a tab which is attachable to 120

- the bottom; and tucking flaps joining end edges of the lid and adapted to be tucked inside the box or to form extensions of the lid; said lid and extensions having a fold line along the main axis of the lid at the edges of the lid and extensions transversely to the latter; the lid being partially cut through from points to points nearer the inner edge of the lid to form a display portion, and collapsible upon itself with said extensions to permit the front flap of the lid to be tucked against the back wall behind material or articles in the container, to hold the lid with said extensions collapsed and the display portion projected upwardly, with its outer face faced forward, said lid embodying severable means secured to said bottom.
8. A container comprising a blank cut and folded to form front rear and end walls foldably joining the edges of the bottom respectively; the front and rear walls being provided at each end with a corner flap secured to the inner face of the end walls; a lid joining the upper edge of the rear wall and provided with a front flap substantially covering the front wall and provided with a tab secured to the under face of the bottom, said tab being scored at the inner edge thereof, to be readily detachable from said front flap; tucking flaps joining the edges of the lid and adapted to be tucked against said corner flaps; said tucking flaps being disposable outwardly to form extensions of the lid; the container, when the end walls and corner and tucking flaps are open being adapted to receive, and be packed with, articles which it is to receive, by means of known packing and filling machines.
- Signed at New York in the county of New York and State of New York this 20th day of April, A. D. 1928.

EDWARD O. TINSLEY.
